HARMONIC-FREQUENCY GENERATOR

Rudolf E. Sturm, Flushing, N. Y., assignor, by
mesne assignments, to Hazeltine Research, Inc.,
Chicago, Ill., a corporation of Illinois

Application September 20, 1941, Serial No. 411,624

1 Claim. (Cl. 250—36)

1

The present invention relates to harmonic-frequency generators and, more particularly, to harmonic-frequency generators of the type adapted to develop in an output circuit thereof a wide range of harmonic components. Such generators have many uses, for example, in frequency-calibrating carrier-signal communication equipment and in multi-channel carrier-signal transmission systems.

Harmonic-frequency generators generally include a piezo-electric crystal-controlled oscillator from the output of which there are derived signal components which are harmonics of the natural frequency of the piezo-electric crystal. In accordance with one prior art arrangement, the harmonic-frequency generator comprises simply a conventional crystal-controlled oscillator so energized and biased that the anode current of the oscillator consists of current pulses occurring at the period of the crystal and of duration short compared to the crystal period. A current of this nature is rich in harmonics of the natural frequency of the oscillator. While this prior art arrangement is fairly simple, it has the disadvantage that the harmonic-frequency components have relatively little energy content and the generator, therefore, may be used only in conjunction with a high gain amplifier which forms a complex and expensive component of the generator or an adjunct thereto.

It has been proposed, in accordance with another prior art arrangement, that a crystal-controlled oscillator be used to synchronize the operation of a multivibrator which develops an output current of substantially rectangular wave form which, as is well known, is rich in harmonics of the natural frequency of the multivibrator. The multivibrator is isolated from the crystal-controlled oscillator and from the output circuit of the generator by buffer amplifiers. Such amplifiers are essential to prevent reaction by the multivibrator on the crystal-controlled oscillator and to prevent the reaction of such circuits and apparatus as are coupled to the output circuit of the generator from affecting the operation of the multivibrator. The prior art arrangements of this nature are, therefore, also unduly complicated and expensive. They have the further disadvantage that it is difficult to construct multivibrators for operation at frequencies higher than about

2

100 kilocycles, due to the inherent circuit and tube capacitances. Thus, it is difficult to develop by such harmonic generators very high-frequency harmonics having any appreciable power.

- 5 5 It is an object of the present invention, therefore, to provide a new and improved harmonic-frequency generator which avoids one or more of the disadvantages and limitations of the prior art devices.
- 10 10 It is another object of the invention to provide a harmonic-frequency generator of simple and inexpensive construction involving a minimum of circuit elements and one which is capable of delivering directly, and without the need of additional amplification, harmonic-frequency components having substantial amplitude, for example, of the order of one volt or more.

15 15 It is an additional object of the invention to provide a harmonic-frequency generator which not only involves a simple and inexpensive construction, but which has great flexibility in its operating characteristics and is adapted to deliver large amplitude harmonic-frequency components over a wide harmonic-frequency range, for example, one which may extend into the high-frequency range well about 10 megacycles.

20 20 In accordance with the invention, a harmonic-frequency generator comprises means for generating primary oscillations of a predetermined fundamental frequency and means for developing secondary oscillations of higher frequency than the primary oscillations. The generator includes means for combining the primary and secondary oscillations to derive oscillations of 25 25 unsymmetrical wave form having a large peak amplitude of given polarity during only one relatively small portion of each cycle. The generator also includes means for clipping the oscillations of the unsymmetrical wave form to derive only 30 30 the peak-amplitude portion effectively comprising a periodic wave of pulse-wave form, of period equal to that of the primary oscillations, and rich in harmonic-frequency components.

35 35 In a preferred form of the invention, a harmonic-frequency generator of the type described comprises means for developing periodically-recurrent damped trains of oscillations and means responsive to the oscillations for deriving a periodic wave effectively of pulse-wave form, of period equal to that of the recurrent oscillation

trains, and rich in harmonic-frequency components. The generator is provided with an output circuit including means for selecting desired ones of the harmonic-frequency components.

For a better understanding of the invention, together with other and further objects thereof, reference is had to the following description, taken in connection with the accompanying drawings, and its scope will be pointed out in the appended claims.

Referring now to the drawings, Fig. 1 is a circuit diagram representing a complete harmonic-frequency generator embodying the invention; Fig. 2 is a graph representing current and voltage relationships occurring at selected points in the arrangement of Fig. 1 and is used in explaining the operation of the invention; Fig. 3 is a circuit diagram of a modified form of the "clipper" system of Fig. 1; Figs. 4 and 6 are circuit diagrams representing modified forms of harmonic-frequency generators embodying the invention; while Figs. 5 and 7 are graphs representing voltage and current relationships occurring at selected points in the respective arrangements of Figs. 4 and 6.

Referring now more particularly to Fig. 1 of the drawings, there is represented a complete harmonic-frequency generator embodying the present invention in a preferred form. The generator includes means for generating primary oscillations of a predetermined fundamental and preferably constant frequency, this means being represented generally by an alternating current source 10. Coupled to the source 10 is an oscillator 11 of the blocking-oscillator type. This oscillator is of conventional form and includes a vacuum tube 12 having its input and output electrodes coupled by a transformer 13, the input circuit including a grid condenser 14 and an adjustable grid resistor 15 for determining the natural frequency of oscillation. Coupled to the input-electrode circuit of the oscillator 11 is means for developing secondary oscillations of higher frequency than the primary oscillations of oscillator 11 comprising a vacuum tube 16 having an inductor 17 included in the anode circuit thereof. The inductor 17 is tuned to a frequency higher than that of the primary oscillations of oscillator 11 by the capacitance represented by the broken-line condenser 18 for the reason that it may be comprised in whole or in part of the distributed capacitance of the inductor 17 and the inherent anode circuit capacitance. The tuned circuit 17, 18 is damped by the total effective resistance r in shunt thereto, thus to determine the decrement of the train of secondary oscillations developed across this circuit. This effective resistance is shown in dotted lines for the reason that it may be comprised in whole or in part of the inherent resistance of the inductor 17, of physical resistance connected across inductor 17, and of the effective resistance of the rectifier device 19 and the resistor 20.

The generator also includes means responsive jointly to the primary oscillations of the oscillator 11 and the secondary oscillations developed by the amplifier 16 to derive a periodic potential effectively of pulse-wave form, of period equal to that of the primary oscillations, of a duration of the order of one-half the period of the secondary oscillations, and rich in harmonic-frequency components. This means comprises a rectifier device 19 and load impedance 20 therefor coupled across the inductor 17 through a resistor 21 included in the anode circuit of amplifier 16, the

unidirectional potential drop across the resistor 21 providing a bias for the rectifier device 19.

The periodic potential of pulse-wave form developed across the load impedance 20 is applied to an amplifier 22. The output circuit of amplifier 22 is coupled to the harmonic generator output circuit which includes means for selecting desired ones of the harmonic-frequency components comprising a harmonic selector system 23 which is provided with a plurality of series-tuned circuits 24, 25, 26 and 27, each being tuned to a predetermined selected harmonic frequency. The coupling between the amplifier 22 and the harmonic selecting system 23 comprises a pair of band-pass selectors 28, 29 which are coupled by a link circuit 30 and which have pass bands sufficiently broad to pass all desired harmonic-frequency components. The use of the link circuit 30 permits the use of the two band-pass selectors 28 and 29, as distinguished from the use of only one such selector, whereby the selectivity of the coupling arrangement is increased and the pass band of the tandem-coupled selectors 28 and 29 is no wider than necessary to pass the desired harmonic-frequency components. The several series-tuned circuits 24-27, inclusive, are coupled to the output terminals 31, 32 of the generator by a plurality of respective coupling condensers 32-35, inclusive, and a selector switch 36. Additional selectivity is obtained by connecting an inductor 37 across the output terminals 31, 32 and by adjusting the several condensers 32-35, inclusive, in such manner that each condenser forms with the inductor 37 a series-tuned circuit resonant at the harmonic frequency to which the series-resonant circuit associated with the particular condenser is tuned.

Considering now the operation of the circuit above described and referring to the curves of Fig. 2, the primary oscillations of source 10 are assumed to be of sinusoidal wave form, as represented by curve A. These oscillations are applied as synchronizing oscillations to the blocking oscillator 11. As is well known, the periodic potential developed across the resistor 15 in the input circuit of oscillator 11 is of generally saw-tooth wave form having a large negative peak amplitude and a small positive peak amplitude, as represented by curve B, the period of this potential being the same as that of the oscillations of source 10. Thus, oscillator 11 comprises means responsive to the oscillations of the source 10 for developing oscillations of distorted wave form and of period equal to that of the oscillations of source 10. When the potential developed across the resistor 15 is applied to amplifier 16, there is developed across the inductor 17 in the output circuit thereof periodically-recurrent damped trains of secondary oscillations of frequency equal to the resonant frequency of the inductor 17 and capacitance 18, this frequency being much higher than that of the primary oscillations of source 10. That is, the rapid rate of increase of the negative potential developed across the resistor 15 during the time intervals t_1-t_2 , t_3-t_4 , etc., shock-excites the tuned circuit 17, 18 to develop therein for each cycle of the primary oscillations a damped train of secondary high-frequency oscillations, as represented by curve C.

These oscillations are of distorted wave form and have a large peak amplitude of given polarity during only one relatively small portion of each cycle due to the damping of the circuit, the decrement of the oscillations depending, first, upon the inherent resistance r of the tuned circuit

comprising inductor 17 and capacitance 18, which may be increased by the addition of a physical resistor, if desired, and, second, upon the values of the resistors 20 and 21 and the resistance in its conductive state of the rectifier device 19. In practice, the first positive half-cycle of each train of oscillations generally has an amplitude appreciably greater than that of any succeeding positive half-cycle. In fact, if the values of either or both the resistor r and the series resistors 20 and 21 are made sufficiently small, the tuned circuit 17, 18 may be so critically damped that only one complete oscillation is developed across the tuned circuit during each of the intervals t_1-t_3 , t_3-t_5 , etc. These damped trains of oscillations are applied to the rectifier device 19 which is so biased by the unidirectional potential across the resistor 21 that it is conductive only during the largest amplitude positive half-cycle of the train of oscillations. This biasing level is represented in Fig. 2 by the broken line a, b . Thus, the rectifier device 19 comprises a clipping system arranged to clip only the peak portion of the first positive half-cycle of each train of oscillations developed across the inductor 17.

There is consequently developed across the rectifier load impedance 20 a periodic potential wave effectively of pulse-wave form, as represented by curve D. This periodic wave has a period equal to that of the recurrent oscillation trains, which, in turn, is equal to the period of the primary oscillations of source 10, and the pulses thereof have a duration of the order of but usually less than one-half period of the secondary oscillations developed across the inductor 17. The periodic potential of curve D is thus rich in harmonic-frequency components and is amplified by the amplifier 22 and applied to the harmonic selector system 23, wherein a desired harmonic-frequency component is selected by operation of the selector switch 36 and applied to the output terminals 31, 32 of the generator.

As illustrative of a specific embodiment of the invention, the following circuit constants are given for an embodiment of the invention of the type shown in Fig. 1:

Vacuum tubes 12 and 16	-----	Type 6N7
Vacuum tube 19	-----	Type 6H6
Transformer 13	-----	
Primary winding inductance	-----	millihenries
Secondary winding inductance	do	136
Mutual inductance	-----	do
Resistor 15 (maximum)	-----	ohms
Resistor 21	-----	do
Resistor 20	-----	do
Condenser 14	-----	micromicrofarads
Inductor 17	-----	millihenry
Frequency of source 10	-----	kilocycles
Frequency of secondary oscillations, (approx.)	-----	megacycle
Source +B	-----	volts

From the above description of the Fig. 1 arrangement, it will be seen that the saw-tooth oscillator 12 and amplifier 16 comprise means coupling the primary oscillation generator or source 10 and the secondary oscillation developing means comprising the inductor 17 and capacitance 18 to synchronize the secondary oscillations with the primary oscillations.

Fig. 3 is a circuit diagram of a modified form of clipper system suitable for use in the system of Fig. 1. This clipper system is essentially similar

to that of Fig. 1, similar circuit elements being designated by similar reference numerals, except that the rectifier device 19 is coupled to the output of the amplifier 16 through a coupling condenser 38 and the cathode of the rectifier device 19 has applied thereto a positive bias from a source of unidirectional potential 40. Additionally, a rectifier device 39 is connected, with polarity opposite to that of the device 19, across the series circuit comprising the device 19, the resistor 20, and the battery 40. The value of the battery 40 is such as to cause the rectifier device 19 to clip at the amplitude level a, b , Fig. 2. The operation of this modified form of clipping system is otherwise essentially similar to that of the clipping system of Fig. 1, except that the rectifier device 39 prevents any charge from building up across the rectifier device 19 due to the rectifying action thereof and also aids in increasing the decrement of the tuned circuit 17, 18.

Fig. 4 is a circuit diagram of a modification of a portion of the harmonic-frequency generator of Fig. 1, similar circuit elements being designated by similar reference numerals. The source 10 of primary oscillations of Fig. 1 is here shown in more detailed form as comprised of a crystal-controlled oscillator 41. The oscillator 41 includes a vacuum tube 42 having input electrodes coupled in conventional manner to a piezo-electric crystal 43 and having output electrodes coupled to a tuned output circuit comprising a variable inductor 44 and anode-circuit inherent capacitance, represented by the broken-line condenser 45, the output circuit being resonant at the natural frequency of oscillation of the crystal 43. The oscillator 41 thus comprises means for generating primary oscillations of a predetermined fundamental frequency equal to the frequency of the crystal 43. The blocking oscillator 11 of Fig. 1 is omitted in the modification of Fig. 4 and the output of the oscillator 41 is coupled directly through a condenser 46 to the input circuit of the amplifier 16 which includes a grid leak 46', the time constant of the condenser 46 and grid leak 46' being sufficiently long that the amplifier 16 is biased beyond cutoff except during a short interval of each positive half-cycle of the oscillations applied thereto from oscillator 41. Amplifier 16 thus operates as a clipper stage. The inductor 17 in the output circuit of the amplifier 16 is here shown as of the adjustable type and it will be understood that it is tuned with capacitance 18 to a frequency much higher than the frequency of oscillations generated by the oscillator 41. The diode rectifier type of clipper system 19 of Fig. 1 is replaced in the arrangement of Fig. 4 by a pentode type vacuum tube 47, the control grid of which is coupled through a condenser 48 to the output circuit of amplifier 16. A grid-leak resistor 49 is connected across the input electrodes of tube 47, the condenser 48 and resistor 49 having values proportioned to develop a self-bias for the control grid of tube 47 in a conventional manner. The remainder of the system is identical to that of Fig. 1.

Considering now the operation of this modification of the invention and referring to the curves of Fig. 5, the oscillator 41 operates in conventional manner to develop across the inductor 44 primary oscillations of a predetermined fundamental frequency corresponding to the natural frequency of oscillation of the piezo-electric crystal 43. The frequency of these oscillations is substantially constant, due to the controlling effect of crystal 43, as is well known.

The primary oscillations are applied to the amplifier or clipper 16 and the anode current thereof occurs in short pulses of the period of the primary oscillations, as represented by curve E. These current pulses shock-excite the inductor 17 and develop thereacross periodically recurrent damped trains of secondary oscillations of frequency higher than that of the primary oscillations, as represented by curve F. These secondary oscillations are applied to tube 47 which acts as a conventional peak rectifier, developing across the resistor 49 a negative self-bias of such value that only the peak of the first positive half-cycle of each train of damped oscillations is repeated by tube 47. There is thus derived in the output circuit of vacuum tube 47 a periodic potential effectively of pulse-wave form, as represented by curve G. This periodic potential corresponds to that of curve D of Fig. 2, is of a similar wave form, and has similar characteristics. The operation of this modified form of the invention is otherwise essentially similar to that of Fig. 1 and will not be repeated here.

As illustrative of a specific embodiment of the invention of the type shown in Fig. 4, the following circuit constants have been found satisfactory:

Vacuum Tubes 42 and 16	Type 6SC7
Vacuum Tube 47	Type 6SJ7
Inductor 44	millihenries 2.82
Inductor 17	microhenries 253
Resistor r (approximately)	ohms 30,000
Resistor 46'	megohm 1.0
Resistor 49	do 1
Condenser 46	microfarad 0.002
Condenser 48	do 0.002
Source +B	volts 250
Source +Sc	do 250
Frequency of primary oscillations	kilocycles 400
Natural frequency of inductor 17	megacycles 2

Fig. 6 is a circuit diagram representing a modified form of harmonic-frequency generator of the invention essentially similar to that of Fig. 1. In this arrangement, the means for generating primary and secondary oscillations is comprised by a single vacuum tube 50. The input electrodes of vacuum tube 50 are coupled in conventional manner to a piezo-electric crystal device 51 and the screen grid of tube 50 is used as an anode element and connected in a first anode circuit comprising a voltage-dropping resistor 52 and shunt-connected condenser 53, a parallel-tuned circuit 54, and a source of energizing potential indicated as +B. The tuned circuit 54 is resonant at the natural period of oscillation of the crystal 51. The anode of tube 50 is included in a second anode circuit comprising a parallel-tuned circuit 55 and is energized from the source of space current +B through the tuned circuits 54 and 55 in series. The tuned circuit 55 is resonant at a frequency which is a harmonic of, and therefore higher than that of, the tuned circuit 54, preferably the fourth harmonic of the latter. The oscillations developed in the tuned circuits 54 and 55 are combined in the anode circuit of tube 50 and are applied through a condenser 56 to a clipper system comprising a pentode vacuum tube 57, the tube 57 having a grid-leak resistor 58 and acting as a conventional peak rectifier. The output circuit of tube 57 includes an inductor 59 having connected in shunt

therewith by selective operation of a switch 60 any one of a plurality of condensers 61-64, inclusive, which tune the inductor 59 to predetermined harmonic-frequency components. The output circuit terminals 65, 66 of the generator are coupled across the inductor 59.

Considering now the operation of this modification of the invention and referring to the curves of Fig. 7, broken-line curve H represents the wave form of the primary oscillations of fundamental frequency developed across the tuned circuit 54, this voltage being fed back principally through the control grid to screen capacitance of tube 50 to the input circuit comprising the crystal 51 to maintain oscillation. It may be noted that the resistor 52 is a voltage-dropping resistor used for the purpose of reducing the screen-grid voltage below that of the anode of tube 50, the condenser 53 by-passing the resistor 52 for currents of the fundamental oscillation frequency. The control grid of tube 50 develops in well-known manner a large self-bias whereby tube 50 operates as a class C oscillator. The screen-grid current of tube 50 consequently is of periodic pulse-wave form and contains a large number of harmonics including a strong fourth harmonic of the fundamental frequency. The screen and control grids of tube 50 effectively modulate the stream of electrons flowing to the anode and there is thus developed across the tuned circuit 55 fourth-harmonic secondary oscillations. The oscillatory voltages developed across the tuned circuits 54 and 55 are combined in the anode circuit of tube 50 and, when properly phased by adjustment of the relative tuning of circuits 54 and 55, produce a resultant output wave of distorted wave form having a large peak amplitude of given polarity during only one relatively small portion of each cycle, as represented by curve I. These latter oscillations are applied to the clipper tube 57 which is effective, as in the previously described modifications, to develop in the anode circuit of tube 57 a periodic potential wave effectively of pulse-wave form as represented by curve K, this potential having a period equal to that of the primary oscillations developed across the tuned circuit 54 and being rich in harmonic-frequency components. A desired harmonic-frequency component is selected by operation of the switch 60 and applied to the output terminals 65, 66 of the generator.

While it has been stated that the tuned circuit 55 is resonant at the fourth harmonic of the oscillations of fundamental frequency developed across the tuned circuit 54, it will be evident that tuned circuit 55 may be resonated to any suitable harmonic frequency, preferably to a higher frequency. This has the effect of narrowing the duration of the pulses of the periodic potential developed in the output circuit of the clipper tube 57 with consequent increase in the range over which the harmonic-frequency components have adequate amplitude to be used directly without additional amplification. The tuning of circuit 55 to the fourth harmonic is desirable, however, for the reason that there is a strong fourth harmonic component in the screen-grid current of tube 50 and for the further reason that the harmonic-frequency components developed by the generator have larger power, the power output of any particular lower harmonic component varying directly with the duration of the pulses of the periodic potential developed in the output circuit of tube 57, whereas the range of harmonic-frequency components of

substantial amplitude varies inversely with the duration of the periodic potential pulses.

As illustrative of a specific embodiment of the type shown in Fig. 6, the following circuit constants have been found suitable:

Vacuum tube 50	-----	Type 1Q5GT
Vacuum tube 57	-----	Type 1Q5GT
Tuned circuit 54		
Inductance	-----	microhenries 200
Capacitance	-----	micromicrofarads 150
Tuned circuit 55		
Inductance	-----	microhenries 70
Capacitance	-----	micromicrofarads 15
Resistor 52	-----	ohms 100,000
Resistor 58	-----	megohms 4.7
Condenser 53	-----	micromicrofarads 500
Condenser 56	-----	do 500
Frequency of primary		
oscillations	-----	kilocycles 800
Frequency of secondary		
oscillations	-----	megacycles 3.2
Source +B	-----	volts 135

It will be evident from the above description of the Fig. 6 modification that the electronic coupling, within tube 50, of the tuned circuits 54 and 55 comprise means coupling the primary-oscillation generating means, which is tuned circuit 54, and the secondary oscillation developing means, which is the tuned circuit 55, to synchronize the secondary oscillations with the primary oscillations.

It will be evident from the above description of the invention that a harmonic-frequency generator embodying the invention has the advantage of great simplicity and economy of construction and is capable of delivering a wide range of harmonic-frequency components of appreciable amplitude. The generator has the additional advantages of a high degree of flexibility of its operating characteristics and can be easily initially adjusted for best operation and, when once adjusted, is stable in operation without further adjustment over long periods of operation.

While there have been described what at present are considered to be the preferred embodiments of the invention, it will be understood by those skilled in the art that various changes and modifications may be made herein without departing from the invention, and it is, therefore, aimed in the appended claim to cover all such modifications and changes as fall within the spirit and scope of the invention.

What is claimed is:

A harmonic-frequency generator comprising, means for generating primary oscillations of a predetermined fundamental frequency, means for developing secondary oscillations of higher frequency than said primary oscillations, means for combining said primary and secondary oscillations to derive oscillations of unsymmetrical wave form having a large peak amplitude of given polarity during only one relatively small portion of each cycle, and means for clipping said oscillations of unsymmetrical wave form to derive only said peak-amplitude portion effectively comprising a periodic wave of pulse-wave form, of period equal to that of said primary oscillations, and rich in harmonic-frequency components.
